OHIO

QUICK-ACTING MECHANISM FOR ELECTRIC SWITCHES AND THE LIKE

Application filed July 18, 1927. Serial No. 206,526.

Our invention relates to electric switches, and more particularly to an automatic cutout for opening and closing electric circuits under the influence of variations of pressure, 5 temperature, or intensity of an actuating medium. While the invention is herein shown and described more particularly in its application to an electric switch it will be understood that the same actuating mechanism 10 may be utilized for opening and closing valves, shifting a clutch into and out of operative position, or to perform other analogous operations. A very usual application of the present type of automatic cutout 15 is the control of domestic type mechanical refrigerators, motor driven pumping systems for water distribution, and compressed air apparatus. Such control or cutout devices are utilized in such systems to maintain pressure or temperature within predetermined 20 range limits by setting in operation an actuating motor, opening a supply valve or by connecting an actuating mechanism whenever the temperature of a chill room or 25 refrigeration chamber, or the fluid pressure within the tank fluctuates beyond the predetermined range and to automatically arrest the motor, or close the valve, as the case may be, when the predetermined normal 30 condition has been restored. In many instances such cutout or control devices have been of a slow moving type having a tendency to dwell or lag under some conditions. The present construction is designed to not 35 only overcome this objection but to provide a construction which will maintain a full, or even increased pressure upon the contact point until the instant of operation, whereupon the disconnection or breakage will be effected with a quick snap-over action, eliminating any tendency to spark or arc between the contact points.

The object of the invention is to simplify 45 the structure, as well as the means and mode of operation, of such quick acting cutout mechanisms, whereby they will not only be cheapened in construction, but will be more efficient in use, positive in operation, uniform in action, automatically controlled, and 50 unlikely to get out of repair.

A further object of the invention is to provide a mechanism having a minimum number of operating parts so shaped and designed that they may be economically manufactured by stamping or by punch press operation, and so arranged as to facilitate assembly. Economy of manufacture and simplicity of construction are of prime importance. 55

With the above primary and other incidental objects in view, as will more fully appear in the specification, the invention consists of the features of construction, the parts and combinations thereof, and the mode of operation, or their equivalents, as hereinafter described and set forth in the claims. 60

Referring to the drawing, Fig. 1 is a side elevation of the assembled mechanism showing the switch parts in their closed or contacting position. Fig. 2 is a similar view showing the switch parts reversed, and the contact broken. Fig. 3 is a side elevation from the right of Figs. 1 and 2. Figs. 4 and 5 are detail views showing the application of the invention to a valve and a clutch respectively. 70

Like parts are indicated by similar characters of reference throughout the several views.

The operating parts of the automatic quick acting cutout mechanism are mounted within a housing 1 with which is connected a pressure chamber 2 having therein a yielding diaphragm fluctuating under variations of fluid pressure, or, as illustrated in the present instance, an expandable and contractible bellows 3 of the "sylphon" type. Carried by such bellows 3 is a stud or thrust member 4 engaged by a helical compression spring 5, against the yielding resistance of which the bellows 3 is actuated by fluid pressure admitted to the chamber 2 through an inlet conduit 6. The tension or compression spring 5 abuts upon a nut or collar 7 carried by an adjustable stud 8 mounted in the wall of the housing 1. By adjustment of the stud 8 the tension or resistance of the spring 4 to movement of the bellows 3 may be regulated. Pivoted upon a stud 9 carried by the housing 1 is a bell crank lever 10, one arm of which pivotally engages with a stud or pin 11 car- 80

ried by the thrust member or bellows stud 4. This bellows stud or thrust member is preferably, though not necessarily, slotted or recessed to receive the end of the bell crank lever 10. The other arm of the bell crank lever 10 is provided with oppositely inclined or beveled end faces 12 and 12', with which a roller 13 carried by a trip arm 14 alternately engages. The trip lever 14 is preferably of hollow or box like formation comprising interconnected spaced side bars between which the roller 13 is located. This trip arm is pivoted at 15 to one end of an oscillatory switch lever 16 pivotally mounted upon the stud 17 carried by the housing or main frame.

The roller 13 carried by the trip arm 14 is yieldingly held in engagement with one or the other inclined face 12—12' of the bell crank lever by a tension spring 18 connected 20 at one end to such arm 14 and at its opposite end to the bell crank lever 10. As a matter of convenience and economy of manufacture the end of the spring 18 is engaged in an irregular opening 19 in the bell crank lever 10 25 through which extends a pin 20 carried by the main frame or housing 1 which serves to limit the oscillation of the bell crank lever 10 in either direction. At its opposite end the spring 18 is adjustably connected to the end 30 of the spring arm 14 by an adjusting nut 21. The trip arm 14 is capable of a limited to and fro reciprocatory movement as the roller 13 engages alternately the inclined faces of the bell crank lever 10. This reciprocation of 35 the trip arm effects an oscillatory movement of the switch lever 16 about its pivotal connection 17 and in turn effects the reciprocation of a plunger 22 connected to the lower end of the oscillatory lever 16. The plunger 40 22 has a sliding bearing in the terminal block 23 of insulating material. Terminals or binding posts 24 upon the block 23 are associated with stationary contacts which are engaged by movable contacts 25 carried upon 45 spring arms 26 connected with the reciprocating plunger.

In Fig. 1 the roller 13 is shown in engagement with the beveled face 12 of the bell crank lever 10 and the switch lever 16 and plunger 50 22 are in their operated positions. The switch contacts 25 are engaged with the circuit terminals upon the terminal bar 23. As the fluid pressure within the chamber 2 decreases, the reaction of the compression spring 5 upon 55 the thrust member or bellows stud 4 tends to oscillate the bell crank lever 10 about its pivotal connection 9. This movement is yieldingly resisted by the roller 13 and tension spring 18. The camming action of the 60 inclined face 12 forces the roller upwardly against the yielding resistance of the spring 18 until the apex of the bell crank lever arm passes beyond dead center relation with the roller 13, shown by dotted lines in Fig. 1, 65 whereupon the reaction of the tension spring

18 together with the camming effect of the inclined face 12' upon the roller 13 will insert a longitudinal or reciprocatory action upon the trip arm 14 thrusting it toward the oscillatory switch lever 16 and oscillating the latter to disconnect the contact members 25 as shown in Fig. 3. As the pressure within the chamber 3 increases a reverse action takes place. The increase of fluid pressure acting upon the bellows or diaphragm 3 and against the expansive action of the compression spring 5 oscillates the bell crank lever 10 in the opposite direction. The inclined face 12' exerting its camming action upon the roller 13 oscillates the trip arm 14 about its pivotal connection 15 against the yielding resistance of the tension spring 18 until the apex of the inclined faces 12—12' passes beyond the dead center relation with the roller 13. Thereupon the reaction of the tension spring 18 exerting pulling influence upon the trip arm 14 draws the roller 13 down the inclined face 12. Inasmuch as the bell crank lever 10 resists movement, the camming action between the roller and inclined face 12 effects a reciprocation of the arm 14 to again oscillate the lever 16 about its pivot 17 to effect contact of the members 25 with their corresponding terminals upon the insulation mounting 23.

While the apparatus has been illustrated in connection with movable electrical switch contacts 25 it will be obvious that the plunger 22 may be extended beyond the housing 1 and be connected with a valve as at 25 in Fig. 4, or with a clutch element 26 as shown in Fig. 5. Otherwise the operation of the device is as before described.

From the above description it will be apparent that there is thus provided a construction of the character described, possessing the particular features of advantage before enumerated as desirable, but which obviously is susceptible of modification in its form, proportions, and arrangement of parts, without departing from the principle involved or sacrificing any of its advantages.

While in order to comply with the statute the invention is described in language more or less specific as to structural features, it is to be understood that the invention is not limited to the specific details shown, but that the means and construction herein disclosed comprise the preferred form of several modes of putting the invention into effect, and the invention is therefore claimed in any of its forms or modifications within the legitimate and valid scope of the appended claims.

Having thus described our invention, we claim:

1. In a quick acting switch mechanism, or the like, an oscillatory cam arm having oppositely beveled faces, means for oscillating said arm, a trip arm engaging one or the other beveled faces of the cam arm, and a spring under the tension of which such en-

gagement is effected said spring having its ends movably mounted, the limited movement of said cam arm being sufficient to shift the point of engagement of the trip arm past the apex of the oppositely beveled faces, the reaction of said spring causing said engaging point to travel upon the beveled face and by the camming action thereon causing reverse movement of the trip arm.

2. In a quick acting switch, an oscillatory cam arm having oppositely inclined faces capable of a limited degree of oscillation, an oscillatory operating lever capable of a degree of oscillation greater than the cam arm, a trip arm pivoted to the operating lever and having engagement with one or the other of the inclined faces of the cam arm, a spring connected at one end to the cam arm and at the other end to the trip arm against the tension of which said trip arm is oscillated by the camming action of the inclined face of the cam arm upon oscillation of the latter during movement from one limit of its range of movement to the other, to enable the engaging point of the trip arm to pass from one inclined face to the other, the reaction of said spring causing said point of engagement to travel upon the inclined face and by the resulting camming action oscillate said operating lever.

3. In a device of the character described, a prime mover having convergent faces and capable of limited to and fro movement, a reciprocating trip arm riding upon one or the other of the convergent faces, a tension spring urging the reciprocating trip arm into engagement with the engaged face, the limited movement of the prime mover serving to present the converging faces alternately for engagement of said reciprocating trip arm said prime mover further changing the tension of said spring according to the direction of its movement whereby the trip arm will move in one direction under greater spring tension than in the opposite direction, the reaction of said spring serving to move the trip arm along the engaged face and by the camming action thereof effect longitudinal movement, and a member to be moved to alternate positions operatively connected with said reciprocating trip arm.

4. In a device of the character described, a prime mover having convergent cam faces, a trip arm having engagement with one or the other of said faces and capable of both oscillatory and reciprocatory movement, said prime mover being capable of limited to and fro movement sufficient to shift the point of engagement of the trip arm past dead center relation in either direction, means for so shifting the prime mover and holding said member against further movement and spring means actuating the trip arm upon the engaged face to afford camming action by which said trip arm is moved longitudinally

and means for varying the tension of said spring in accordance with the direction of movement of the prime mover.

5. In an apparatus of the character described, a pivoted bell crank lever, one end of which is provided with oppositely beveled cam faces, means for applying pressure in alternate directions to the other arm of said lever to effect oscillation thereof, stop means limiting the lever to a short range of action, a pivoted operating lever, a trip arm pivoted to said operating lever and resting upon one or the other of said beveled cam faces, and a spring connected to the crank lever and tending to move the trip arm upon the engaged cam face to effect reciprocation of said arm, and consequent oscillation of the operating lever, and means for oscillating the bell crank lever to present the beveled faces alternately in position for engagement of said trip arm the tension of said spring being changed accordingly as one bevel face or the other is presented in engagement with said trip arm.

6. In an apparatus of the character described, a pivoted bell crank lever, means engaging one end of the bell crank lever for oscillating it in alternate directions, a reciprocating trip arm having operative engagement with one arm of the crank lever, a spring connected with the other arm of said crank lever and actuating the trip arm in alternate direction in accordance with the movement of the crank lever, the movement of the crank lever in one direction serving to increase the operative tension of said spring, and its movement in the opposite direction tending to decrease such operative tension.

7. In a quick acting switch mechanism, a prime mover, a movable trip member, and a spring against the tension of which the trip is movable to alternate position, said spring being connected to the prime mover and the trip member and tensioned by the relative movement of said members, the tensioning effect being to different degrees during the operation of the mechanism into and out of contact engaging condition.

8. In a quick acting switch mechanism, a prime mover, a trip member movable to alternate positions, and a spring connecting the trip member and prime mover, said prime mover and trip member having movement in the same direction to effect movement of the trip member in one direction under which the spring is tensioned to minimum degree and movable in opposite directions to effect the movement of the contact member in a reverse direction under which the spring is tensioned to maximum degree.

9. In a snap over switch, a trip member movable to alternate positions, an actuating spring therefor, said spring member having its ends movably mounted, a movable control member coacting with the trip member

and by its change of position determining the direction of movement of the trip member, said spring being variably tensioned in accordance with the direction of movement of the control member.

10. In a snap over mechanism, an operated member movable to alternate positions, an actuating spring therefor and a control member governing the movement of the actuated member and simultaneously varying the tension of the actuating spring whereby the actuated member is moved in one direction under greater spring tension than in the opposite direction.
15. In testimony whereof, we have hereunto set our hands this 10th day of July, A. D. 1927.

WALTER H. WEINRICH,
FREDERICK CARL GEILER.
